UNITED STATES PATENT OFFICE

OSKAR JOHAN GUSTAF KÄRE, OF ALSTEN, SWEDEN

ATOMIZER FOR INTERNAL COMBUSTION MOTORS

Application filed November 7, 1929, Serial No. 405,358, and in Sweden July 21, 1928.

The present invention relates to fuel atomizers for internal combustion motors of the type which are driven with liquid fuel injected in a liquid state into the combustion chamber. In motors of this type, the fuel is frequently injected immediately before the combustion is to take place. Consequently, it must be introduced in such a manner that mixing with the compressed air is effected as quickly and effectively as possible. The greatest mixing efficiency is obtained in such cases when the fuel is injected through a plurality of comparatively small nozzle openings. The mixing efficiency is then further increased by making the relation between the circumference and the cross-sectional area of these nozzle openings as great as possible, the contacting surface between the fuel jets and the compressed air being increased thereby. The present invention has for its object to facilitate provision of the desired number of nozzle openings of any desired cross-sectional shapes.

The accompanying drawings illustrate a fuel nozzle according to the invention. Fig. 1 is a longitudinal section of part of the cylinder of an oil motor having such a nozzle. Fig. 2 shows an embodiment, partly in section, of the atomizer nozzle on an enlarged scale.

In Fig. 1, A represents the motor cylinder and B the combustion chamber having inserted therein the nozzle a, to which fuel is supplied through the pipe C. The fuel nozzle a is provided at the bottom with a centrally arranged, outwardly flared conical opening. Fitted into this opening is a sleeve f which externally fits accurately to the conical opening, and the inner surface of which is also conical, although with a smaller cone angle than the outer surface. A stud b is fitted accurately into the sleeve f. The sleeve f as well as the stud b fitted into the same are provided on their external conical surfaces with a number of grooves e¹, e, respectively, approximately parallel to the generatrixes of the conical surfaces.

Inwardly toward the nozzle, the stud b is provided with a threaded extension c having a nut d screwed thereon, said nut abutting

against the bottom of the nozzle and thus keeping the stud b and the sleeve f in their positions in the conical nozzle opening. The nut d is provided at the bottom with grooves g intended to admit the fuel to the grooves e¹ and e.

The number of grooves may be further increased by the arrangement of two or more sleeves between the body of the nozzle and the stud b, and these sleeves are all formed analogously to the sleeve f and, like the latter, they are all provided externally with grooves to increase the number of fuel jets in the combustion chamber.

The cone angle for the outermost cone may evidently be increased indefinitely up to 180° or more, in which case the jets emanating from the same are all situated in one plane, or, form a cone directed toward the nozzle. By the arrangement described all points within the combustion chamber may thus be supplied with fuel in the form of jets of any dimensions and any cross-sectional shape.

What I claim as new and desire to secure by Letters Patent of the United States of America is:—

1. A fuel atomizing device for internal combustion engines comprising a hollow nozzle inclusive of an end wall having an outwardly flared conical opening formed therethrough, a conical sleeve fitting said opening, said sleeve having an outwardly flared conical opening formed therethrough of a smaller cone angle than the cone angle of the opening in said nozzle, a conical stud fitting the conical opening in said sleeve, one of the pair of abutting faces between said nozzle and said sleeve and one of the pair of abutting faces between said sleeve and said stud having fuel channels formed therein, a threaded member on said conical stud extending into said nozzle, a nut separate from said nozzle threaded on said member against the inner face of the end wall of the nozzle to hold said stud and said sleeve in assembly with the nozzle, said nut having slots for the passage of fuel from the interior of the nozzle to said channels, and means for the admission of fuel to the interior of said nozzle.

2. A fuel atomizing device for internal combustion engines comprising a hollow nozzle inclusive of an end wall having an opening therein, stud means disposed in said opening and providing channels for the passage of fuel from the interior of the nozzle to the exterior thereof, a threaded member carried by said stud means and extending into the nozzle, a nut separate from said nozzle threaded on said member against the inner face of the end wall of the nozzle to hold said stud means in assembly with the nozzle, said nut having slots for the passage of fuel from the interior of the nozzle to said channels, and means for the admission of fuel to the interior of said nozzle.

In testimony whereof I affix my signature.
